ATTORNEY.

UNITED STATES PATENT OFFICE.

JOSEPH J. TOMKINSON, OF FORT WAYNE, INDIANA.

IRONING MACHINE.

Application filed June 11, 1926. Serial No. 115,253.

The invention relates to ironing machines and it is directed particularly to the type wherein the ironing members are carried by a cabinet or other enclosure, adapted to receive the same when not in use.

Ironing machines generally in household use are portable and require storage space when not in use. Frequently storage space is difficult to arrange and it is the object of the invention to provide a machine that is supported in novel manner in a cabinet installed at a convenient place, as in the wall of a building, from which cabinet the ironing members are withdrawn when used.

The invention is illustrated in the accompanying drawings, in which

Figure 1 is an elevational view of the device in operating position; Fig. 2 an end view of the same; Fig. 3 an end elevational view showing the rollers in horizontal position ready to be swung into the cabinet; Fig. 4 a front elevational view, the rollers being enclosed in the cabinet; Fig. 5 an enlarged cross-section on line 5—5 of Fig. 1; Fig. 6 a view similar to Fig. 1 illustrating a modification of the roller shifting mechanism; Fig. 7 an end view of the same; Fig. 8 a front view of the modified device enclosed in the cabinet and Fig. 9 a cross-section on line 9—9 of Fig. 6.

Referring to the illustrative embodiment of the invention 1 represents a cabinet or other form of enclosure or housing that may be portable or disposed in the wall of a building. An electric motor 2 is mounted on a wall of the cabinet upon the shaft 3 of which is secured a worm 4 that meshes with a gear 5 mounted upon a spindle 6 secured to the rear wall of the cabinet. A socket member 7 is formed on the outer side of the gear 5 through the walls of which a pin 8 extends. The inner wall of the socket at its forward end flares somewhat.

A rod or pipe 9 extends across the cabinet and is suitably supported upon the opposite side walls thereof. A frame member 10 is pivotally mounted on the rod 9 and on this member are two bearings 11 and 12 that swing thereon. The bearings are spaced on the member 10 sufficiently to receive the upper roller 13 between them. A shaft 14 is secured to one end of the roller 13 and is adapted to be received by the socket 7, the end of the shaft being notched to engage the pin 8 and thereby form a clutch. This shaft is borne by the bearing 11. The heat-

ing member 15 is supported in the bearing or hanger 12 and extends into the roller 13. In the drawings the heater is of the gas type, the fuel being supplied through the conduit 16, the portion 17 of which is flexible, but any form of heater may be used. A curved guard 18 is attached to the member 10 and extends over the roller.

Below the spindle 6 and secured to the rear wall of the cabinet is a socketed boss 19 that is adapted to receive the free end of a pipe or member 20 that is connected to a pipe or member 21, which latter member is connected to the bearing 11. A shaft 22 is fixed to the member 21 and projects therefrom in a plane parallel to the axial plane of the shaft 14. This shaft 22 extends into the lower roller 23, and a sleeve 24 within the roller is mounted on the shaft and projects from the roller a sufficient distance for the crank 25 to be secured thereto. A rod 26 is pinned to the crank and its lower end is slidable on a post 27 to which post a cup 28 or other form of rest is engaged. A pedal 29 is suitably attached to the rod 26 by which to reciprocate the rod to cause the crank to rotate the sleeve.

Two cam lugs 30 and 31 are formed on or secured to the sleeve 24 near the opposite ends of the roller 23. A bracket 32 is secured to the member 21 and supports and guides a spider 33 having a roller 34 at the outer end of each of its arms that engages the inner surface of the roller 23. The arm 32^a of the spider extends loosely through the guide bracket 32 and carries a flange 33^b at its lower end that is adapted to contact with the sleeve 24 and to be engaged by the cam lug 31 when the sleeve is rotated, by which cam the spider is elevated to raise the roller toward the upper roller 13. A bracket 34 is secured to the shaft 22 and extends into the roller 23. A spider 35, similar in all respects to the spider 33, is slidably supported in this bracket 34 and engages the inner surface of the roller 23. The cam lug 30 on the sleeve 24 elevates the spider 35 and roller simultaneously with the operation of the spider at the opposite end of the roller. The spacing of the sleeve and the driving shaft 14 determines the normal spacing of the two rollers 13 and 23 and the cams 30 and 31 are the proper height to cause the lower roller to contact with the upper roller when desirable.

If desirable, a roller 36 may be mounted between the bracket 32 and a bracket 37

also mounted on the member 21. This roller frictionally engages both rollers 13 and 23 and will tend to cause the upper roller to drive the lower roller. The lower roller may 5 be driven in any suitable manner if that should be desirable.

The actuating rod 26 may be removably pinned to the crank so that it may be separated therefrom when the rollers are swung 10 into the cabinet.

When the rollers are extended outwardly as shown in Fig. 1 they are supported on the rod 9 and braced by the member 20 that is engaged in the boss 19. The electric current 15 being turned on, the motor drives the gear 5 and the socket or clutch member 7 which drives the shaft 14 and the upper roller. By depressing the pedal the lower roller is moved toward the upper roller and the ironing operation is performed. When the sleeve 24 is retracted the cams are moved from under the 20 spiders in the lower roller and the roller descends by gravity to normal position.

To insert the rollers into the cabinet they 25 are rocked upwardly on the rod 9 to disengage the shaft from the socketed member 7 and the member 20 from the boss 19 and the unit is then turned on the support 10 to a substantially horizontal position as shown in 30 Fig. 3. The unit is then swung downwardly on the rod 9 into the cabinet as shown in Fig. 4, where it is fully enclosed. The reverse steps are taken to withdraw the roller 35 unit. A door may be hung on the front of the cabinet to close it.

In Figs. 6 to 9 a modified form of the shifting mechanism for the lower roller is shown in which the lower roller 23 is revolubly mounted on a shaft 38, one end of 40 which is extended through a slot formed in the pipe or member 21^a and the opposite end of which is extended through a slot 39^a in a member 39. This member 39 is mounted on a pipe 40 and the pipe 21^a is connected to the 45 bearing 11 and to a union 41 on the pipe 40. A plunger 42 is longitudinally slidably mounted in the member 39 and its upper end engages the shaft 38 and its lower end engages a cam 50 formed on the pipe by flattening the pipe the proper amount. A spring 43 bears against the flange 44 at the upper end of the plunger 42 and also engages a rib 45 in the member 39 through which the plunger is passed. A similar plunger 46, 50 with a spring 46^a thereon, is similarly disposed in the pipe 21^a and in the union 41 and similarly engages the shaft 38 and a cam 47 similar to the cam 50.

A shaft 48 is secured to one end of the pipe 60 40 and a crank 49 is connected to the shaft. The rod 26, is removably connected to the crank and by depressing the pedal 29 the rod is reciprocated downwardly to rotate the pipe 40 and cause the cams 47 and 50 to elevate 65 the plungers and the roller 23. The other

end of the pipe is adapted to engage in the socketed boss 19.

In all other respects the device of Fig. 6 is similar to Fig. 1 and is similarly supported for movement into and out of the cabinet. 70

The rollers are readily withdrawn from the cabinet or receptacle 1 and firmly braced in horizontal position so that the ironing operation is effectively carried on with ease. When not in use, the rollers being moved into 75 the cabinet or receptacle, the device is out of the way and occupies a minimum of space.

Numerous modifications in the construction and arrangement of the parts are possible, the form above described being illustrative only. 80

What I claim is:

1. In an ironing machine, a receptacle, a fixed support in the receptacle, a frame pivotally mounted on the support and adapted 85 to be swung from a vertical position in the receptacle to a horizontal position exteriorly of the receptacle, driving means within the receptacle, cooperating ironing rollers pivotally mounted on the frame and adapted to swing laterally as a unit thereon, and means connected to one of the rollers and adapted to be connected to the driving means for rotating the rollers. 90

2. In an ironing machine, a receptacle, a support fixed within the receptacle, a frame mounted on the support and adapted to swing thereon in a vertical plane from a position within the receptacle to a horizontal position exteriorly of the receptacle, a pair 100 of cooperating ironing rollers on the frame and adapted to swing as a unit laterally thereon, means to rotate the rollers and means having engagement with one of the rollers to move it bodily toward the other roller. 105

3. In an ironing machine, a receptacle, a support fixed within the receptacle, a frame mounted on the support and adapted to swing outwardly thereon in a vertical plane from a vertical position to a horizontal position, driving means mounted in the receptacle, a pair of cooperating rollers pivotally mounted on the frame for unitary lateral swinging movement thereon, a shaft secured to one of the rollers and adapted to be connected to the driving means, and means engaging the other roller to move it bodily toward the first roller. 110

4. In an ironing machine, a receptacle, a pivotally mounted frame normally depending within the receptacle and adapted to be swung outwardly to a horizontal position, means having a connection to the frame and adapted to engage the receptacle for supporting the frame in horizontal position, a pair of 125 rollers pivotally mounted on the frame for movement in a plane at right angles to the plane in which the frame is movable, a driving mechanism within the receptacle, a shaft on one of rollers adapted to be engaged to the 130

driving mechanism when the frame is in horizontal position, means to heat said roller, a shaft within the other roller, a cam-carrying sleeve revolubly mounted on the shaft, means to rock the sleeve and means having engagement with the inner wall of the latter roller and adapted to be reciprocated by the cams on the sleeve when the sleeve is rotated to move said roller toward the heated roller.

10 5. In an ironing machine, a roller, a shaft to drive the roller, a second roller normally spaced from the other roller, a fixed shaft within the second roller, a revoluble cam-

carrying sleeve on the fixed shaft, a spider having an arm normally engaging the surface 15 of the sleeve and adapted to be engaged by the cam, and having rollers at the outer ends of other arms engaging the inner wall of the roller and means connected to the sleeve for rotating it to cause the cam to engage the 20 first named arm and elevate the spider and the roller.

In witness whereof I have hereunto set my hand this 10th day of June, 1926.

JOSEPH J. TOMKINSON.
